UNITED STATES PATENT OFFICE.

SIDNEY H. SHORT, OF CLEVELAND, OHIO, ASSIGNOR TO THE SHORT ELECTRIC RAILWAY COMPANY, OF SAME PLACE.

CROSS-OVER FOR TROLLEY-LINES.

SPECIFICATION forming part of Letters Patent No. 447,208, dated February 24, 1891.

Application filed October 22, 1890. Serial No. 368,994. (No model.)

To all whom it may concern:

Be it known that I, SIDNEY H. SHORT, of Cleveland, in the county of Cuyahoga and State of Ohio, have invented certain new and useful Improvements in Cross-Overs for Trolley-Lines of Electric Railways; and I do hereby declare the following to be a full, clear, and exact description of the invention, such as will enable others skilled in the art to which it appertains to make and use the same.

This invention relates to the means for carrying one trolley-line or supply-conductor of an electric railway over or across another in such a way as to allow the trolleys to pass on either line. Heretofore I have devised and patented a cross-over for this purpose (see my patent, No. 422,096, dated February 25, 1890) in which a notched bridge, preferably of insulating material, is provided on one line and the other or crossing-line is supported by an insulator on said bridge in the notch thereof. The trolleys on the last-mentioned line, therefore, pass through the notch under the first-mentioned line, which is carried over the bridge, while those on said first-mentioned or bridge line pass along the bridge and across the notch. The present invention has more particular reference to cross-overs of this description; but each of the improvements constituting said invention is included for all the uses or applications to which it may be adapted. One at least of such improvements is applicable to trolley-lines otherwise than in cross-overs—as, for example, in frogs or switches.

In accordance with the present invention the cross-over is composed of an arch, preferably of metal, provided with means for retaining the conductor in arched position—that is to say, with a curve at the cross-over upward above its normal level—and with one or more track-pieces, preferably of insulating material, on which the trolley runs in making the crossing. By this improvement the bearing for the trolley at the crossing may be brought more in line with the conductor on either side thereof. Further, by employing a metal arch in connection with a track-piece or track-pieces of wood or insulating material strength is secured without sacrificing efficiency. Preferably the means for retaining the conductor in arched position consist

of clips, which inclose the conductor and are fastened to the arch. Further, the bottom of the arch is made wider than the conductor and is grooved to receive the same, the clips passing through slots in the arch. The track piece or pieces are preferably placed between depending ears or flanges on the arch and secured by bolts or pins passing through the ears or flanges and the interposed track-piece. A clip incloses the conductor and the adjacent end of the track-piece.

The cross-over is provided with a holder for the insulating-support of the transverse trolley wire or conductor, and this holder is in the present invention formed by a divided socket, one half formed in a suitable part of the arch or an attachment thereto—such as a bracket—and the other constituted by a removable piece. The insulating-support is held in the socket. The said holder is best formed in or by a lateral arm or bracket, so that the insulating-support for the transverse trolley-wire is at one side of the cross-over.

The invention extends to the cross-over provided with the holder for the transverse trolley-wire in a lateral arm or bracket irrespective of the form of the holder, as well as when said holder is formed by a divided socket.

Another feature belonging to the present invention consists in an insulating track-piece of wood in two or more thicknesses or laminæ secured together with their grain in different directions, the tread or track-bearing being formed on the edge of the track-piece by the edges of one or more of the thicknesses or laminæ. Preferably this "laminated" track-piece increases in width above the bearing-surface for the trolleys, which surface is formed by the edge of one of the thicknesses or laminæ. A solid bearing is thus given for the trolleys to travel on, while at the same time the additional layers impart stiffness and decrease the liability of warping.

The laminated track-piece may be used in connection with or without a suitable frame of metal or other material of any desired form as well as with an arch.

The new or improved cross-over may be used on single or on double trolley-lines.

In the accompanying drawings, which form part of this specification, Figure I is a side

view of a cross-over constructed in accordance with the invention, showing the line-conductors in place. Fig. II is a plan of the same. Fig. III is a cross-section on line *iii* of Fig. I. Fig. IV is a section on line *iv* of Fig. I. Fig. V is a side view of a part of the track-piece, broken away in places to exhibit its laminated structure; and Fig. VI is a side view, on a smaller scale, of a double-wire cross-over constructed in accordance with the invention, the clips being omitted, as well as the conductors and the insulating supports of the transverse conductors.

The conductor A of the trolley-line in which the cross-over is placed is secured to the under side of the brass arch B by means of the clips 2, which hold it in an upwardly bent or arched position. The arch B is provided with a groove 3 underneath to receive the conductor A and has lateral flanges 4, between which the groove 3 is formed. The clips 2 pass through openings 5 in these flanges and their ends are bolted or riveted to the flat-faced lumps 6 on the sides of the web 7 of the arch.

The track-piece C of the cross-over is placed under the conductor B with its upper part between the depending ears 8 of the arch A, and is there secured by bolts or pins 9. The clips 2 at the ends of the track-pieces have toes 2', which extend under the said ends and assist in supporting the said track-piece as well as protecting the joint between it and the conductor B.

The track-piece shown (see Figs. IV and V) consists of three thicknesses or laminæ of wood secured together by cement, with the grain in the layers running in different directions. The middle lamina extends beyond the others, and its under edge constitutes the tread or bearing-surface 10 of the track-piece, which is thickened above by the additional laminæ.

The track-piece C is notched at 11 for the passage of the transverse trolley-wire or conductor D, whose insulating-support E E', consisting of the support E and insulator E', is held in the holder F, constituted by the bracket projecting from the side of the arch A above the notch 11. This bracket may be cast on or otherwise made in one piece with the arch, as shown in Figs. I, II, and III, or may be bolted or otherwise fastened thereto, as shown in Fig. VI. Where there are more than one transverse conductor, a corresponding number of notches 11 may be made in the track-piece C.

The insulator E' of the support E is held in a socket formed by the stationary part 12 on the arch and the removable piece 13, which is bolted thereto. A rib 14 on the inside of the socket engages a corresponding groove on the outside of the insulator.

Having fully described my invention, what I claim as new, and desire to secure by Letters Patent, is—

1. The cross-over composed of an arch, means for securing the conductor or trolley wire in an arched position thereon, and a separate track-piece secured within the arch, substantially as described.

2. The cross-over composed of a metal arch, means for securing the conductor or trolley wire in an arched position thereon, and the track-piece of wood or non-conducting material secured within the arch, substantially as described.

3. The grooved arch, in combination with the conductor or trolley wire laid in an arched position in said groove, and the retaining-clips, substantially as described.

4. The arch comprising a web with side flanges at the bottom and provided with a groove between said flanges, in combination with the conductor or trolley wire in said groove, and the retaining-clips, substantially as described.

5. The cross-over comprising the arch with depending ears, the track-piece secured to the arch through said ears, and the means of securing the conductor or trolley wire on the arch, substantially as described.

6. The grooved arch provided with depending ears, in combination with the conductor or trolley wire in the groove, the retaining-clips, and the track-piece fastened to the arch through said ears, substantially as described.

7. The combination, with the arch, the conductor or trolley wire, and the track-piece, of a clip under the said conductor and track-piece across the joint at the end of said track-piece, substantially as described.

8. A clip provided with a toe, substantially as described.

9. A clip provided with a toe, in combination with an arch to which the clip is secured, a conductor or trolley wire in the clip, and a track-piece whose end overlies said toe, substantially as described.

10. A cross-over comprising a notched track and provided with a holder for the insulating-support of the transverse conductor or trolley wire, said holder consisting of a socket above the notch, one part of which socket is stationary on the cross-over and the other is a removable piece, substantially as described.

11. A cross-over comprising a notched track and provided with a bracket projecting laterally from the cross-over above the notch and carrying the holder for the insulating-support of the transverse conductor or trolley wire, substantially as described.

12. A cross-over comprising, first, a metal arch provided with a bracket-holder for the insulating-support of the transverse conductor or trolley wire; second, means for securing to said arch the conductor or trolley wire in which the cross-over is placed, and, third, the track-piece having the opening for the transverse conductor below the said holder, substantially as described.

13. A track-piece composed of a number of

thicknesses of wood secured together with their grain in different directions and arranged to present one of its edges as a bearing-surface for the trolley or traveler, substantially as described.

14. A laminated track-piece having the surface formed by the edge of an intermediate thickness or lamina, substantially as described.

15. A cross-over comprising a notched laminated track-piece, the thicknesses or laminæ being of wood secured together with the grain in different directions, and the bearing-surface at the edge of said laminae, substantially as described.

16. A laminated wooden track-piece, in combination with a metal frame, substantially as described.

17. A cross-over comprising a metal arch and a laminated wooden track-piece secured to said arch with the bearing-surface at the edge, substantially as described.

In testimony whereof I have signed this specification in the presence of two subscribing witnesses.
